UNITED STATES PATENT OFFICE.

THOMAS B. ZELLER, OF KOSSUTH, ASSIGNOR OF ONE-HALF TO F. S. BOWMAN, OF TYLERSBURG, PENNSYLVANIA.

COMBINATION-LOCK.

SPECIFICATION forming part of Letters Patent No. 366,806, dated July 19, 1887.

Application filed March 12, 1887. Serial No. 230,678. (No model.)

To all whom it may concern:

Be it known that I, THOMAS B. ZELLER, a citizen of the United States, residing at Kos-
suth, in the county of Clarion and State of
Pennsylvania, have invented a new and use-
ful Improvement in Combination - Locks, of
which the following is a specification.

My invention relates to improvements in
combination-locks, with a view to making a
simpler and cheaper form thereof adapted for
use in connection with padlocks, post-office
boxes, cupboards, drawers, &c., in addition to
the ordinary situations in which such locks
are used.

My invention consists, further, in certain
details of construction, hereinafter more fully
described, pointed out in the claims, and clearly
illustrated in the accompanying drawings, in
which—

Figure 1 is a perspective view of the lock.
Fig. 2 is a rear elevation of same. Fig. 3 is a
similar view with the rear plate removed. Fig.
4 is a central longitudinal section on the line
x x of Fig. 2. Fig. 5 is a rear view with the
device locked.

Referring to the drawings by letter, A des-
ignates the body of the lock, having front plate,
B, and rear plate, C; and D is the sliding bolt
of the lock, having a round opening or bear-
ing, d, near the front end, and a slot, d', in the
rear end.

E is a knob having a circular flange, F, to
rest on the face of the lock-plate, and G is a
spindle or post rigid with the said knob and
passing through the slot b in the front plate,
the circular opening or bearing d in the bolt
D, and projecting a short distance beyond the
same.

E' is a knob similar to E, having a flange,
F', spindle G', rigid with said knob and pass-
ing through an opening, b', in the plate, and
also through the slot d' in the rear end of the
bolt and projecting a short distance beyond the
same. On the rear or inner ends of the said
spindles G G' are placed the disks or tumblers
H H', respectively, the tumbler H having the
integral tongues I I on one side adapted to fit
into the corresponding recesses, I' I', in the

disk H', so that when the said tongues and re-
cesses align properly the bolt D may be pushed
back by moving the spindle G (which is se-

cured in the said bolt and the tumblers H)
backward in the slot b by means of the knob E.

I² represents a slight shoulder on the said
spindle G, slightly above the inner surface of
the bolt D, which shoulder is adapted to serve
as a stop, against which the tumbler H is bound
by the set-screw K, inserted in the end of the
said spindle to cause the said spindle and tum-
bler to turn together. I⁴ is a similar shoulder
on the spindle G', adapted to serve as a stop
for the tumbler H', which is bound firmly in
position by means of the set-screw K' in the
end of the said spindle G'. i i' are washers
under the heads of the set-screws. It will be
seen that the said set-screws may be very read-
ily loosened to turn the tumbler on the spin-
dle and then tightened again to bind it firmly
thereto.

There is a series of numbers or letters around
the flange of each of the knobs, and an indi-
cator or mark on said flange to point to a cer-
tain letter, and when the proper combination-
letters are indicated by the said marks or in-
dicators, the tongues and recesses on the tum-
blers will align properly and allow the bolt to
be drawn back. A small circular opening, P,
is made in the rear plate over or in line with
the spindle G to enable the set-screw to be op-
erated to change the combination, and a simi-
lar opening, P', is formed around the spindle
G' for a similar purpose.

It will be noticed that a great number of
combinations can be made with the improved
lock, and the said combinations can be very
easily made by simply loosening the set-screws
and turning the spindle in the tumbler until
the indicator on the knob points to the desired
letter or number on the disk, and the said com-
bination may be changed at any time that the
door is opened, since the means of setting the
combination is exposed at such times.

The construction of the lock (namely, with
two tumblers, one being secured to and movable
with the bolt and the other being stationary) 95
is very simple, and yet much more difficult to
unlock than when only a single tumbler is
provided, and, further, a greater number of
combinations may be thereby made.

The construction of my device being so sim-
ple and so compact in form adapts it especially
for use in padlocks and similar situations where

the space occupied is an item of consideration, and the evident cheapness of manufacturing the lock should commend it to the notice of the public and cause it to be generally used in many situations—such as drawers, cupboards, &c.—where the ordinary key-locks are now used, as it is obviously more convenient to remember a combination than to carry a key of one of the said locks, and in the former case to there is no danger of rendering the lock useless by losing the said key.

Having thus described my invention, I claim—

1. A combination-lock having the sliding bolt, combined with the tumblers H H', one of which is stationary and the other movable with the said bolt, substantially as described.

2. A combination-lock having the sliding bolt, the stationary tumbler H', and the knob E'; to rotate the same, combined with the knob E, having the spindle G, to pass through a slot in the face-plate of the lock and journaled in an opening in the bolt, and the tumbler H, adapted to be rotated by the said handle E, substantially as described.

3. A combination-lock having the sliding bolt D, combined with the stationary tumbler H', adapted to be rotated by the knob E and having the recesses I' I' in one side, and the tumbler H, journaled in and movable with the 30 said bolt and adapted to be rotated by the handle E, said tumbler having the tongues I I to fit in the recesses I' I', and adapted, when aligned with said recesses, to allow the said bolt D to be drawn back, substantially as described. 35

4. A combination-lock having the sliding bolt D, combined with the stationary tumbler H', having the knob E' and the tumbler H journaled to the said bolt, and having the handle E, the said tumblers H H' being adapted 40 to be independently adjusted on their respective spindles to form the desired combination, substantially as and for the purpose specified.

In testimony that I claim the foregoing as my own I have hereto affixed my signature in 45 presence of two witnesses.

THOMAS B. ZELLER.
